CLAIM

The ornamental design for a clothing separator, as shown and described.

DESCRIPTION

FIG. 1 is a perspective view of a clothing separator showing my new design with the broken line showing of hangers and support rod being for illustrative purposes only and forming no part of the claimed design;

FIG. 2 is a left end elevational view of the clothes separator as shown in FIG. 5, along the plane indicated by line 2;

FIG. 3 is a right end elevational view of the clothes separator as shown in FIG. 5, along the plane indicated by line 3;

FIG. 4 is a top plan view of the clothes separator as shown in FIG. 1;

FIG. 5 is a side elevational view of the clothes separator as shown in FIG. 1; and,

FIG. 6 is a bottom plan view of the clothes separator as shown in FIG. 1.
